WITNESS:

UNITED STATES PATENT OFFICE.

ROBERT B. TAYLOR, OF BALTIMORE, MARYLAND.

FIRE BOX.

Application filed March 30, 1920. Serial No. 369,912.

To all whom it may concern:

Be it known that I, ROBERT B. TAYLOR, a citizen of the United States, residing at Baltimore, State of Maryland, have invented 5 new and useful Improvements in Fire Boxes, of which the following is a specification.

This invention relates to fire box arches, and comprehends a construction wherein 10 the bricks of the arch are associated to prevent of their being separated incident to the vibration of the locomotive. Arch bricks with which I am familiar, are provided with a narrow shoulder that rests 15 upon the water cooled pipe and the vibrations of the locomotive causes these bricks to separate and fall into the fire before adhesion takes place, thus resulting in the loss of the bricks as well as other troubles. 20 It is therefore the purpose of this invention to construct the bricks used in the production of the arch, in a manner whereby an overlapped joint is provided for the meeting ends of the bricks, thereby making 25 it impossible for the bricks to become separated incident to the vibration of the locomotive.

The nature and advantages of the invention will be better understood when the following detailed description is read in connection with the accompanying drawings, the invention residing in the construction, combination and arrangement of parts as claimed. 30

In the drawings forming part of this specification, like numerals of reference indicate similar parts in the several views and wherein:—

Figure 1 is a plan view of one of the arch 40 sections constructed in accordance with my invention.

Figure 2 is a longitudinal sectional view therethrough.

Figure 3 is a plan view of one of the bricks 45 used in the construction of the arch.

Figure 4 is an edge elevation.

Figure 5 is an end elevation of one of the bricks.

Figure 6 is a transverse sectional view 50 through one of the bricks.

Figure 7 is a plan view of the arch showing a modified construction.

Figure 8 is an edge elevation.

The arch contemplated by the invention is 55 made up of the desired number of sections such as illustrated in Figure 1, each sec-

tion preferably including three bricks of the type shown. The two end bricks of each section as indicated at 10 while the intermediate brick is indicated at 11. The meeting ends of these bricks are cut away as at 12 to receive a portion of the water cooled pipe 13 in the usual manner, these cut away portions defining shoulders 15 which rest upon the pipes as illustrated. With a view 60 of firmly holding the bricks in arched formation, and thereby preventing these bricks from becoming separated incident to the vibrations of the locomotive, I provide each of the end bricks 10 upon one side with a thickened or raised portion 16, each of which is formed or provided with a recess 17. Carried upon one side of the intermediate brick 11 and at each end thereof is a pair 65 of lugs 18, each pair projecting an appreciable distance beyond the adjacent end of the brick. These lugs 18 are, when the bricks are arranged in arched formation received by the recesses 17, thus providing an overlapped joint at the meeting ends of the 70 bricks as is obvious. In other words, the lugs 18 bridge the meeting ends of the respective bricks 10 and 11 and overlie the water cooled pipe 13, an arrangement which 75 positively prohibits separation of the bricks 80 incident to the vibration of the locomotive, thus preventing the bricks from dropping into the fire resulting in numerous troubles. 85

In Figures 7 and 8 I have illustrated a modified form of the invention, wherein the 90 respective sections of the arch indicated at 20, have their meeting ends cut away as at 21 to receive a portion of the water cooled pipe 23, these cut away portions defining shoulders 24 which rest upon the pipe as 95 illustrated. In this form of the invention lugs 25 arranged in pairs project from one end of each of the end sections of the arch, while similar lugs 26 project in pairs from both ends of the intermediate section of the 100 arch, and when the sections are arranged end to end, the lugs 25 and 26 bridge the meeting joints between the sections, and bear upon the surface of the adjacent section as clearly shown in Figure 7. It is to be understood that any number of bricks may be 105 employed in the production of the arch, and the lugs carried by the respective sections are arranged in a proper manner to overlie or bridge the joint between the ends of the 110 sections.

While it is believed that from the fore-

going description the nature and advantages of the invention will be readily apparent, I desire to have it understood that what is herein shown and described is merely illustrative, and that I do not limit myself in this connection and that such changes may be resorted to when desired as fall within the scope of what is claimed.

Having thus described my invention what 10 I claim as new is:—

A fire box arch comprising spaced sections and an intermediate section, said sections being arranged in end to end relation, the adjacent ends of the respective sections

being cut away, said cut away portions of the respective sections unitedly defining substantially semi-cylindrical recesses, the upper surface of said spaced sections being provided with raised portions having slots opening at the ends of the sections, and lugs 20 carried by the intermediate section and projecting beyond the ends thereof and adapted to be received by said slots, overlapping the spaced sections for the purpose specified.

25 In testimony whereof I affix my signature.

ROBERT B. TAYLOR.
